UNITED STATES PATENT OFFICE.

WILLIAM THOMAS BUCKINGHAM ROBERTS, OF LEICESTER, ENGLAND, ASSIGNOR, BY
MESNE ASSIGNMENTS, TO UNITED SHOE MACHINERY CORPORATION, OF PATERSON,
NEW JERSEY, A CORPORATION OF NEW JERSEY.

SEWING-MACHINE.

1,264,686.

Specification of Letters Patent. Patented Apr. 30, 1918.

Application filed March 19, 1915. Serial No. 15,521.

To all whom it may concern:

Be it known that I, WILLIAM T. B. ROBERTS, a subject of the King of Great Britain, residing at Leicester, in the county of Leicestershire, England, have invented certain new and useful Improvements in Sewing-Machines; and I do hereby declare the following to be a full, clear, and exact description of the invention, such as will enable others skilled

10 in the art to which it appertains to make and use the same.

The invention relates to sewing machines used in the manufacture of boots and shoes, and particularly concerns tack pulling devices applicable for use in such machines.

As is well known by those skilled in the art, it is usual in lasted shoes to secure the shoe upper to the insole and last by tacks partially driven into the last. In subsequent operations, such, for example, as attaching the welt to the lasted shoe, these tacks often cause trouble as by contacting with the sewing needle or for other reasons, and it is therefore desirable to remove some 25 or all of the lasting tacks prior to performing further operations upon the shoe.

It is an object of the present invention to provide a sewing machine for use in the manufacture of boots and shoes with an improved tack pulling device which is actuated yieldingly when moved toward the tack, and positively when withdrawing the tack from the work, while another object of the invention is to arrange that such a tack pulling device may be rendered operative or inoperative at will without interrupting the normal operation of the machine, whereby the operator can remove such tacks as he may deem desirable for the proper performance of the sewing or other operation on the work.

With these objects in view, a feature of the invention is for a sewing machine for use in the manufacture of boots and shoes, the combination with the tack pulling device of mechanism for actuating the tack pulling tool in a closed path in such a manner that the tool can yield toward the middle of its path, but is positively or unyield-

ingly actuated in a direction at right angles 50 thereto, that is tangentially of its path.

Preferably, and according to another feature of the invention, a tack pulling tool is combined with mechanism under the control of the operator by which the said tool 55 during the sewing or other operation of the machine may be thrown into or out of operation.

The arrangement of the yielding actuation of the tack puller avoids the liability 60 of damage to the work that has been found in practice to exist when a part of the shoe for any reason projects into the normal operative path of the tack pulling tool by 65 which there is a possibility of damage by reason of the fact that the tool digs into the shoe, cutting or otherwise injuring the leather. The yielding operation of the tack pulling tool, according to this invention, insures that it will slide over the surface of the 70 work should it happen to come in contact therewith.

According to another feature of the invention, the arrangement is such that the tack pulling tool when thrown out of operation 75 will stop with certainty in a position out of contact with the work, so that the tool will offer no obstruction to the manipulation of the shoe in the normal operation of the machine.

Preferably, and as hereinafter described, the arrangement according to a feature of the invention comprises a member which is normally axially disposed in relation to a rotary part so that no motion is imparted 80 to the tack pulling tool with which it is connected but which when displaced from such axial alignment, by connections controlled by the operator, impart to such tool a motion toward or from the shoe to eject 85 tacks therefrom. The said member may be displaced from such axial alignment to a greater or less extent to vary the motion imparted to the tack pulling tool and the extent of such variations may be accomplished 90 by the judgment of the operator in using the controlling means or predetermined by the employment of adjustable lim-

iting devices. Preferably the said member may consist of a bar pivoted within a slot in a shaft and acted upon by springs so arranged that the tack pulling tool will be 5 yieldingly actuated by that component of the thrust of the bar upon the tool which lies in the direction of the springs and positively actuated by the component of the thrust which lies transversely to the slot in the 10 shaft.

A preferred construction, according to the present invention, will now be described, reference being made to the accompanying drawings. The invention as herein described and illustrated is embodied in the well-known Goodyear welt and turn shoe sewing machine, which is disclosed with substantial accuracy in the specification of the patent to Eppler, No. 1,108,560, dated 15 20 August 25, 1914. It is to be understood, however, that the specific example herein-after described as a preferred embodiment is capable of modification as regards its construction and the arrangement of the several parts of the same, without departing 25 from the spirit of the invention.

In the drawings, Figure 1 is a side view of part of the said shoe sewing machine, showing a tack pulling tool and operating 30 mechanism therefor, according to the preferred embodiment of this invention;

Fig. 2 is a front elevation of the part of the machine shown in Fig. 1, with portions broken away;

Fig. 3 is a section corresponding in point of view with the front elevation, Fig. 2;

Fig. 4 is a view showing in detail the tack pulling tool; and

Fig. 5 is a transverse section on the line 40 45 5-5, Fig. 2.

Like reference characters indicate like parts in all the figures.

The sewing machine illustrated in the drawings is provided with the usual stitch forming devices, including the curved needle 10, the awl or feed point 12, channel guide 14, back gage 16, and back rest or bunter 18. Reference is hereby made to the above mentioned patent for a detailed description of the construction and operation of the machine, since only enough of the machine has been illustrated to show the association of the tack pulling device therewith.

In the preferred construction the tack pulling device is carried in a bracket 20 which is secured to or formed as part of the frame 22, the said bracket being situated in front of the machine beneath the 50 sewing instrumentalities, and the device is arranged to be thrown into operation by movement of a lever (not shown) actuated by the knee of the operator. The device comprises a tack pulling tool 24 that oper-

ates to withdraw the lasting tacks from a 65 lasted shoe in advance of the action of the needle in the sewing operation. As is usual in tack pulling devices the tool 24 when in operation is given movement in what is approximately an elliptical path, and acts 70 to dig beneath the head of a tack and engage the shank thereof to eject the tack from the work, the acting end of the tool being chisel-shaped in order to more readily dig beneath the head of a tack that may 75 have been driven further than usual into the work. The tack pulling tool 24 is provided with a screw threaded shank portion 26 (see Fig. 4) that is adjustably secured by means of a nut 28 in one end of a bar 30, the other end of which is received in a recess in the enlarged end or head 32 of a slide 34 that is reciprocated and oscillated by means presently to be described. The bar 30 is capable of longitudinal adjustment in the said recess and is secured in adjusted position by means of a screw 36 threaded in the head 32. By means of these adjustments the tool 24 may be set to engage accurately beneath the heads of the 90 tacks.

The head 32 of the slide has a slot 38 in which is received a roll 40 which serves as a guide to the movements of the slide 34. The end of the slide opposite to the tool is 95 cup-shaped to receive a ball 42 secured upon a stud 44 that is screwed into the end of a bar 46 pivoted at 48 in the slot or recess 50 in a shaft 52. A plug 54 whose inner end is also cup-shaped is screwed into the 100 lower end of the slide 34 and serves to retain the ball 42 in position. This construction constitutes a universal joint connection between the pivoted bar 46 and the slide 34. The shaft 52 is surrounded by a fixed 105 collar 55 clamped in a bearing on the bracket 20, and the shaft 52 can be rotated through the pulley 56 from any suitable source of power. The bar 46 is pivoted to the shaft 52 by means of a pin 48 passing 110 through the axis of the shaft and at right angles thereto. Normally the bar 46 is held in axial alinement with the shaft 52 by means to be described, so that the ball 42 revolves about an axis passing through its 115 center and consequently imparts no movement to the slide and the tack pulling tool carried thereby. If, however, the ball 42 is moved so as to be eccentric to the shaft, the ball 42 acts virtually as the pin of a crank 120 and in co-operation the slot 38 and roller 40 impart oscillating and reciprocating movements to the slide 34, which movements cause the tool 24 to travel in an approximately elliptical path 58, as indicated 125 in dotted lines in Fig. 1. The arrangement and position of the parts thus far described are such that when the ball 42 is in its cen-

tral position to throw the device out of operation, the position shown in Fig. 1, the tool cannot fail to come to rest in a position out of contact with the work, thus leaving the 5 work unobstructed and causing no interruption of the sewing operation.

The means for maintaining the ball 42 in central position and for rendering it eccentric to the shaft 52 when it is desired to 10 throw the tack pulling tool 24 into operation will now be described. To the end of the stud 44 carrying the ball 42 is secured a second ball 60 which engages a conical recess 62 formed in a sliding shaft 64, the 15 axis of the recess 62 being in line with the axis of the rotating shaft 52. Seated in the pivoted bar 46 are coiled springs 66 which engage the bottom of the slot or recess 50 in the rotating shaft 52, and tend 20 to turn the bar 46 about its pivot 48, pressing the ball 60 against the surface of the conical recess 62. This recess ends in a cylindrical hole 68 concentric with the axis of the shaft 64 and of the same or slightly 25 larger diameter than the ball 60, so that when the sliding shaft 64 is shifted in one direction the ball 60 enters the hole 68 and the bar 46 and ball 42 revolve about their own axes concentrically with the 30 rotating shaft 52. When the sliding shaft 64 is shifted in the opposite direction the ball 42 leaves the hole 68 and engages the wall of the conical recess 62, being pressed against the said wall by the coil springs 66, 35 and, as will now be described, the ball 42 describes a circular path about the axis of the shaft 52 and imparts movement to the slide 34 and tool 24. The greater the amount of shift of the sliding shaft 64, the 40 larger will be the circle described by the ball 42, and consequently the greater the amount of movement of the tool 24, so that the amplitude of the path of the tool may be varied according to the amount of shift imparted to the sliding shaft 64.

From the fact that the ball 60 is spring pressed against the wall of the conical recess 62 it will be understood that the tack pulling tool 24 is operated in a manner such that 50 it can always yield toward the middle of its path. This yielding quality is of particular advantage in that should the under side of the tool strike the surface of the work for any reason in the tack pulling operation, the 55 tool will not cut into the work, but owing to the yielding of the coil springs 66, will slide over the surface of the work without damaging it. By the bar 46 being pivoted within the slot or recess 50 of the rotary 60 shaft 52, the tool is positively actuated tangentially of its path so that when the latter is rotated to bring the tack pulling tool beneath the head of the tack, the spring 66 will no longer be operative, the bar 46 bear-

ing on the sides of the recess, and the thrust 65 of the tack against the tool being taken up by the pivot 48. The tool will thus give a positive unyielding pull to the tack in the direction of its movement in withdrawing the tack from the work.

The sliding shaft 64 is carried in a bearing 70 on the bracket 20 and is shifted longitudinally by means of a link 70 connecting a pin 72 passing through a slot in the sliding shaft 64 with an arm 74 extending laterally 75 from a vertical rock shaft 76. The rock shaft 76 is provided with a knee lever (not shown), so that the operator can shift the sliding shaft 64 and thereby throw the tack pulling tool 24 into or out of action at will 80 without interrupting the sewing operation. The sliding shaft 64 carries a pin 78 that extends through a slot in the bearing, the pin 78 serving to limit the amount of movement imparted to the sliding shaft by abutting 85 against adjustable stop screws 80 carried in lugs 82 formed on the bearing. As will be understood, it is possible with the construction described for a skilled operator to adjust the path of movement of the tack pulling 90 tool during the operation of the device as he may deem necessary or desirable by merely shifting the position of the knee lever and thus causing the ball 42 to engage a different portion of the conical recess 62 95 in the sliding shaft 64. By adjusting one of the stop screws 80 the maximum amplitude of the path of movement of the tool 24 may be varied in accordance with the work to be operated upon.

The roll 40 that serves as a guide for the tool operating slide 34 is mounted upon a spindle 84 carried in two limbs of a tilting frame 86 that is clamped by means of a bolt 88 upon the collar 54 previously 105 mentioned, the said limbs serving as lateral guides for the slide 34. By loosening the clamping bolt 88 the frame 86 may be turned about the collar 54 and the slide and tool swung downward away from the work 110 when it is not desired to make use of the tack pulling tool. An adjustable stop screw 90 held in a laterally projecting lug of the tilting frame is adapted to abut against the frame 22 of the machine, and serves to position the tilting frame 86 so that the tool is correctly placed with regard to the work when the device is again required to be made use of.

The nature and scope of the present invention having been indicated, and the preferred embodiment of the invention having been specifically described, what is claimed as new is:—

1. A sewing machine, having, in combination, stitch forming devices, a tack pulling device associated therewith, and means under the control of the operator for bring-

ing the tack puller into operative position with relation to the work during the operation of the stitch forming devices.

2. A sewing machine, having, in combination, stitch forming devices, a tack pulling device including a tack pulling tool associated therewith, means for operating the tool in a closed path adjacent the work, and means permitting yielding movement of the tool toward the center of its path while maintaining its operative connection to its operating means.

3. A sewing machine, having, in combination, stitch forming devices, a tack pulling device including a tack pulling tool associated therewith, means for operating the tool in a closed path adjacent the work, means acting continuously to exert positive pressure on said tool tangentially to the path, and means to allow the tool to yield toward the center of its path.

4. A sewing machine, having, in combination, stitch forming devices, a tack pulling device including a tack pulling tool associated therewith, means for operating said tool, and means for adjusting said operating means to vary the path of movement of the tool.

5. A sewing machine, having, in combination, stitch forming devices, a tack pulling device including a tack pulling tool associated therewith, means for moving the tool relatively to the work, and means under the control of the operator for varying the path of movement of the tool during the sewing operation.

6. A sewing machine, having, in combination, stitch forming devices, a tack pulling device including a tack pulling tool associated therewith, means for operating said tool, means for adjusting said tool with relation to the work, and means for adjusting the operating means to vary the motion imparted to the tool.

45 7. A sewing machine, having, in combination, stitch forming devices, a tack pulling device including a tack pulling tool associated therewith, a continuously rotatable shaft for operating the tool, and means to set the tool in operative position above the work and to withdraw it to inoperative position away from the work while the shaft continues to rotate.

8. A sewing machine, having, in combination, stitch forming devices, a tack pulling device including a tack pulling tool associated therewith, a rotatable shaft for operating said tool, means to set said shaft to place the tool in operative position upon the work and to set said shaft so that the tool will be in inoperative position and away from the work.

9. A sewing machine, having, in combination, stitch forming devices, a tack pulling

device including a tack pulling tool associated therewith, a continuously rotatable shaft for operating the tool, means to set said shaft to hold said tool in an inoperative position, and means to set said shaft to move the tool in a fixed path in an operative position upon the work.

10. A sewing machine, having, in combination, stitch forming devices, a tack pulling device including a tack pulling tool associated therewith, a rotating shaft for operating the tool, connections between said shaft and tool, and means to set said shaft so that the tool remains stationary at one setting of the shaft and moves in a fixed path at other settings of the shaft.

11. A sewing machine, having, in combination, stitch forming devices, a tack pulling device including a tack pulling tool associated therewith, a rotating shaft for operating the tool, connections between said shaft and tool, means to set said shaft so that the tool remains stationary at one setting of the shaft and moves in a fixed path at other settings of the shaft, and means to set the shaft while it continues to rotate.

12. A sewing machine, having, in combination, stitch forming devices, a tack pulling device including a tack pulling tool, a rotatable shaft for operating the tool, means to set the shaft to vary the movement of the tool, and mechanism for controlling the movement of the setting means.

13. A sewing machine, having, in combination, a tack pulling device associated therewith, a rotatable shaft for operating said device, a bar pivotally mounted in said shaft connected with said device, and means for setting said bar whereby said connection will be axially arranged with relation to the shaft, so that no motion is imparted to the device or to set the bar whereby said connection will be eccentrically arranged with relation to the shaft so that motion is imparted to the device.

14. A sewing machine, having, in combination, stitch forming devices, a tack pulling tool associated therewith, a rotatable shaft for operating said devices, a bar pivotally mounted in said shaft and connected with said device, means to set the bar to rotate eccentrically with relation to the shaft, and yielding means between the bar and shaft whereby said bar may yield toward an axial alignment with respect to the said shaft while rotating eccentrically.

15. A sewing machine, having, in combination, stitch forming devices, a tack pulling device associated therewith, a shaft for operating said device, a bar pivoted in said shaft having a swivel connection with said device, a member having a conical recess for supporting the end of said bar, and means to adjust said member to set the bar for

movement either concentrically or eccentrically with respect to said shaft.

16. A sewing machine, having, in combination, stitch forming devices, a tack pulling device associated therewith, a frame for supporting said tack pulling device, and means permitting the frame together with

the tack pulling device to be moved away from the stitch forming devices.
